UNITED STATES PATENT OFFICE.

ERNEST KAYFES, OF AHMEEK, MICHIGAN.

SAFETY DEVICE FOR AEROPLANES.

Application filed February 9, 1923. Serial No. 618,070.

To all whom it may concern:

Be it known that I, ERNEST KAYFES, a citizen of the United States, residing at Ahmeek, in the county of Keweenaw and 5 State of Michigan, have invented new and useful Improvements in Safety Devices for Aeroplanes, of which the following is a specification.

This invention relates to safety devices 10 for aeroplanes, the general object of the invention being to provide parachutes for checking the fall of the plane if the engine should stop or some other accident happen which would cause the aeroplane to drop.

15 Another object of the invention is to provide trip means, operated by the pilot, for releasing the parachutes when an accident happens.

This invention also consists in certain 20 other features of construction and in the combination and arrangement of the several parts, to be hereinafter fully described, illustrated in the accompanying drawings and 25 specifically pointed out in the appended claims.

In describing my invention in detail, reference will be had to the accompanying drawings wherein like characters denote like or corresponding parts throughout the several views, and in which:—

Figure 1 is a side view of an aeroplane showing the parachutes in folded position.

Figure 2 is a view showing the parachutes as supporting the aeroplanes.

35 The remaining figures are detail views.

In these views 1 indicates the aeroplane which is provided with a well 2 in which is folded a large parachute 3. This parachute is connected by the cables 4 with the fore and aft parts of the ship, as shown at 40 5. A small parachute 6 is connected by the cable 7 with the top of the large parachute 3. This small parachute is normally supported in folded position on the rear edge 45 of the top plane 8 of the ship by means of the hook 9, which is pivoted between the forked rear end of a bracket 10 which is secured to the plane. The free end of the hook carries a roller 11 and its pivoted part 50 it rounded and provided with the teeth 12, these teeth being engaged by the latch arm 13 of the lever 14 which is pivoted to the bracket 10, as shown at 15. A cable 16 has one end connected with the lever 14 and 55 said cable extends to a point where it can be easily grasped by the pilot. A throw

lever 17 is pivoted intermediate its ends to the bracket 10 and a contractile spring 18 and an expansion spring 19 tend to hold the lever with its forks 20 in raised position. 60 The lever is adapted to be held in lowered position, against the action of the springs, by having its forked end engaged by the hook 9 when the same is in lowered position. The lever 17 is adapted to be moved to 65 lowered position, so that the hook 9 can engage the same, by means of the gear 21 pivotally arranged on the lever 17 and adapted to be manually rotated by means of a handle 22, and the rack bar 23 which has 70 its hooked end engaging a staple 24 on the bracket, said rack bar passing through a guide on the lever so that it can be engaged by the gear 21.

It will thus be seen that by rotating the 75 handle 22 the action of the gear on the rack bar will cause the lever 17 to be lowered against the action of its springs until its forked end can be engaged by the hook 9. The hook 9 will be held in lowered position and in engagement with the forked end 80 of the lever by means of the latch arm 13 engaging its teeth 12. The forked end of the lever will hold the small parachute in position at the rear edge of the plane. If 85 an accident should happen which would cause the ship to drop the pilot would pull on the cable 16, thus moving the latch arm 13 out of engagement with the teeth 12 so that the springs 18 and 19 would jerk the 90 forked end of the lever 17 upwardly and so throw the small parachute upwardly and away from the plane. As soon as the small parachute opened it would jerk the large parachute out of its well and thus the two 95 parachutes would act to check the fall of the ship. In this way the ship would gradually descend to the ground without damage to itself or the occupants.

Instead of operating the latch arm by a 100 cable this arm may be actuated by a system of levers 25 from a foot pedal 26 which is located at a point where it can be conveniently reached by the pilot or operator. A spring 27 holds the levers in a neutral position.

It is thought from the foregoing description that the advantages and novel features of my invention will be readily apparent.

I desire it to be understood that I may 110 make changes in the construction and in the combination and arrangement of the sev-

eral parts, provided that such changes fall within the scope of the appended claims.

What I claim is:—

1. A safety device for aeroplanes comprising a pair of parachutes, a well in the body of the ship for one parachute, cables for connecting said parachute with the body of the ship, a cable connecting the second parachute with the top of the 10 first parachute, means for normally holding the second parachute upon the top plane of the ship and means actuated by the pilot for releasing the second parachute so that it can pull the first parachute from the well.
- 15 2. A safety device for aeroplanes comprising a large parachute connected with the body of the ship, a well in said body for receiving the parachute, a small parachute connected with the top of the first parachute, means for holding the small parachute in folded position upon one of the planes

of the ship, such means including a spring actuated member for throwing the small parachute upwardly and means actuated by the operator for releasing the holding means. 25

3. A safety device for aeroplanes comprising a large parachute connected with the body of the plane, a small parachute connected with the large parachute, a lever having a forked end for engaging the small 30 parachute, spring means for holding said lever in raised position, a hooked member engaging the lever for holding the same in lowered position, a latch member for the hook member, a cable for permitting the 35 latch member to be released by the operator and manually operated means for lowering the lever so that it can be engaged by the hooked member.

In testimony whereof I affix my signature.

ERNEST KAYFES.
